United States Patent Office.

GUSTAV JEDAMSKI, OF NEW YORK, N. Y., ASSIGNOR TO WILLIAM STAEHLEN, OF THE SAME PLACE.

Letters Patent No. 67,120, dated July 23, 1867; antedated July 14, 1867.

PEN-RACK.

The Schedule referred to in these Letters Patent and making part of the same.

TO ALL WHOM IT MAY CONCERN:

Be it known that I, GUSTAV JEDAMSKI, in the city, county, and State of New York, have invented a new and improved Pen-Rack; and I do hereby declare that the following is a full, clear, and exact description thereof, enabling those skilled in the art to fully understand and use the same, reference being had to the accompanying drawing, in which—

Figure 1 represents a sectional front view of this invention.

Figure 2 is a transverse section thereof.

Similar letters of reference in the several figures indicate like parts.

This invention relates to the peculiar form and construction of the spring-jaws, which serve to clamp and retain pens, pencils, or other similar articles placed between them.

A represents a stand or bed-plate, made of sheet metal or any other suitable material, in any desirable form or shape. From this bed-plate rise the spring-jaws B, which are arranged in pairs at suitable distances apart, as clearly shown in the drawing. These spring-jaws, instead of being made of a simple straight piece of sheet steel, as heretofore, are curved, so that a recess, *a*, is formed between them capable of receiving and holding a pen, pencil, or other similar article, and the parts *b*, above this recess, are curved out, and they form springs for themselves, whereby the entrance of the article to be held is facilitated, while the parts *c* of the spring-jaws below the recess *a* also form springs, which begin to act after the upper springs *b* have been forced apart to a certain distance. By these means each spring-jaw forms a double spring, one above and one below the recess *a*, and neither of these two springs is overstrained, as the pens, pencils, or other articles are forced in between them or removed from the same. I am thus enabled to produce durable spring-jaws of sheet brass, whereas the old spring-jaws could not be manufactured successfully of anything else but sheet steel.

My spring-jaws can be stamped and made in a cheap and expeditious manner, and they are less liable to lose their elasticity or to get out of order than the old spring-jaws made of sheet steel and tempered, and the cost of the pen-rack is thereby materially reduced.

What I claim as new, and desire to secure by Letters Patent, is—

The spring-jaws B formed with a recess *a*, and double springs *b* *c*, substantially as and for the purpose described.

GUSTAV JEDAMSKI.
